(57) **CLAIM**

The ornamental design for a camera for automobile, as shown and described.

DESCRIPTION

FIG. 1 is a front perspective view of a camera for automobile showing my new design.

FIG. 2 is a front elevation view thereof.

FIG. 3 is a back elevation view thereof.

FIG. 4 is a left side elevation view thereof.

FIG. 5 is a right side elevation view thereof.

FIG. 6 is a top plan view thereof; and,

FIG. 7 is a bottom plan view thereof.

The broken lines depict portions of the camera for automobile in which the design is embodied that form no part of the claimed design.
